UNITED STATES PATENT OFFICE

157,351

VEHICLE

Edgard C. De Smet, Toledo, Ohio, assignor to Willys-Overland Motors, Inc., Toledo, Ohio, a corporation of Delaware

Application October 20, 1948, Serial No. 149,194

Term of patent 14 years

(Cl. D14—3)

To all whom it may concern:

Be it known that I, Edgard C. De Smet, a citizen of the United States, residing at 2643 Goddard Road, Toledo, county of Lucas, and State of Ohio, have invented a new, original, and ornamental Design for Vehicle, of which the following is a specification, reference being had to the accompanying drawings, forming part thereof.

In the drawings,

The characteristic features of my design reside in the portions shown by means of full lines in the drawings.

What I claim is:

The ornamental design for a vehicle, as shown and described.

EDGARD C. DE SMET.
